CLOSURE FOR WASHING BOWLS, SINKS,
AND PLUMBING FIXTURES

Louis A. Kirschner, Chicago, Ill.

Application August 28, 1946, Serial No. 693,442

3 Claims. (Cl. 4—287)

1

This invention relates to closures for washing bowls, sinks, plumbing fixtures and the like, and more particularly to the plug and sleeve construction used in connection therewith.

One of the objects is to provide a construction wherein the plug will be maintained and positioned in any of its moved positions without requiring any further manipulation of the plug.

Another object is to provide a plug which is normally maintained in its sleeve against unauthorized removal, but which can be removed and reinserted by a slight manipulation of the plug.

Another object is to provide a construction which is simple and inexpensive to manufacture and easy and efficient to operate.

Other objects will become apparent as this description progresses.

Fig. 1 is a cross sectional view of my preferred form showing the plug in closed position.

Fig. 2 is a perspective view of the plug used in the preferred form.

Fig. 3 is a cross sectional view taken on line 3—3 of Fig. 1.

Fig. 4 is a cross sectional view showing a modified construction.

Fig. 5 is a cross sectional view showing another construction.

Fig. 6 is a cross sectional view showing still another construction, and

Fig. 7 is a cross sectional view taken on line 7—7 of Fig. 6.

Referring to the construction shown in Fig. 1, the usual wash basin 20 has a water discharge orifice 22 and an overflow passage 24. The upper end of the orifice is beveled to form a seat for the flange portion 26 of the metal sleeve 28. Interposed between the flange portion and the basin is a gasket 27. The sleeve 28 has a pair of oppositely positioned openings 30 which communicate with the overflow passage 24. The lower portion of the sleeve is threaded as at 32 and extends through the bottom of the basin. Threadedly engaged with the lower portion of the sleeve is a discharge pipe 33 which leads to a sewer fixture not shown. The discharge pipe locks said sleeve in fluid tight engagement with the wash basin.

The plug or valve stopper indicated generally at 34 is formed preferably of one piece of metal material, shaped to form a circular disk or head 35 and a body portion 36. The head has a beveled edge 37 which seats on the complementary shaped portion of the sleeve. The body 36 has a plurality of spaced apertures 38 which form the

2

discharge openings and which also communicate with the overflow passage. The body is also provided with a plurality of (preferably four) equally spaced trackways, generally indicated at 40, each of which is formed of a vertical slot 42 which communicates with a horizontal slot 44 and an outlet slot 46 which leads outwardly of the body portion. The vertical slot 42 extends below its communicating horizontal slot as at 48, thereby forming a stop or interrupter member 50, to prevent accidental removal of the plug member and to keep it operating in a vertical direction.

The body of the plug springs out adjacent its lower end and when stamped can be made so that the metal portion 52 which forms the bottom of the body can be urged slightly outwardly so that as the plug moves in the sleeve there will be a friction tight fit between it and the sleeve, and the plug will maintain itself in any raised position and will also provide a more fluid type seal when in closed position. The natural resiliency of the metal of the plug by virtue of the slotted portions will increase the frictional fit between the plug and sleeve. In Fig. 2, the plug is shown constructed with a taper with the circumference of the body greatest at the bottom. The plug has suitably secured to the top thereof a knob 21 to which is secured the ring 23, by means of which the plug is raised and lowered.

Stamped from the body of the sleeve 28 and bent inwardly at right angles thereto are four fingers 54 which meet and form a cross guide member, generally indicated at 56, and more clearly shown in Fig. 3. The guide member co-operating with the slots 42, 44 and 46 of each of the trackways, serves to position and limit the vertical movement and the horizontal rotation of the plug 34.

The operation of the construction shown in Figs. 1 to 3 is as follows:

The plug 34 can be initially inserted or reinserted after its removal by aligning the slots 46 with the guide fingers, then pushing the plug downwardly until it is stopped, then rotating it clockwise so that the slot 44 passes through the guide fingers until same strike the end of the slot, then the plug is pushed downwardly where the slot 42 passes through the guide fingers. The plug is shown in closed position in Fig. 1. In normal operation, the plug is moved only in a vertical direction to raise and lower same and the slot 42 will be in engagement with the guide fingers. The portion 50 adjacent the bottom of

the slot 42 will act to prevent any accidental rotation of the plug and will keep it in its straight vertical path. However, should it be desired to remove the plug for cleaning and the like, the plug is raised so that the slot 44 is brought in alignment with guide fingers, then the plug is rotated counterclockwise so that the slot 44 passes through the fingers until the fingers hit the edge of the slot, then the plug is further raised to permit it to be removed through the outlet slot 46.

With this construction I have provided a plug body and sleeve, each formed of one piece of material which will have the resiliency to maintain the plug in any of its placed positions and which can be operated, inserted and removed with a minimum of effort and time. With the type of trackway, an unauthorized removal of the plug from the sleeve is difficult, for unless one is familiar with the trackway construction he will cause the plug to move up and down.

Fig. 4 shows a modified construction. The sleeve 58 has a plurality of guide arms 60 which support a ring 62. The plug 64 suitably supports as at 66 a pair of outwardly bowed spring arms 68 which ride within the ring 62 to support and position the plug 64 in any of its raised positions. The plug has a plurality of trackways 70, similar to those described in connection with plug 34, and these operate similarly thereto, with the guide arm 60.

In Fig. 5, I provide a sleeve 72 which has a plurality of struck-out fingers 74, which engage the plug 76, to hold same in any raised position. The sleeve 72 is provided with a plurality of cross bars 78 which support a ring 80 having a keyway 82. The plug 84 supports a rod 86 which rides in the ring 80. The rod has a key 88. When it is desired to remove the plug from the sleeve, the key 88 is aligned with the keyway 82 and withdrawn therethrough. Normally the plug will be moved vertically up and down and held in any placed position by virtue of the friction fit caused by the fingers 74 cooperating with the plug 76.

In Figs. 6 and 7, I show another modification. The sleeve 89 has cross bars 90 and a ring 91. The ring has a keyway 92. The plug 93 supports a rod 94 secured to the top of the plug as at 95. The rod is internally bored as at 96, and has a slotted opening 97. Suitably anchored in the rod by means of a screw 98 is leaf spring member 99 which is bowed outwardly and extends outwardly of said slot, to engage the ring 91. The plug 93 can be positioned and maintained in any such position by said means. To remove the plug, it is rotated until the screw 98, which also acts as a key, is aligned with the keyway 92, and then it is drawn upwardly through said keyway 92.

What I desire to secure by Letters Patents is:

1. A closure comprising a sleeve, a plug having a plug body slidable in said sleeve, guide means on said sleeve, a plurality of equally spaced trackways in said plug cooperating with said guide means, each of said trackways comprising a first

vertical slot, a horizontal slot communicating therewith and a second vertical slot communicating with said horizontal slot and leading downwardly and outwardly of said plug, said first vertical slot extending below the communicating horizontal slot and providing an interrupter member to prevent accidental removal of said plug, the lower portion of said plug body adjacent the second vertical slots being resilient and expanded outwardly and so constructed and arranged to frictionally engage said sleeve and maintain the plug in any of its raised positions.

2. A closure comprising a sleeve, a plug having a plug body slidable in said sleeve, guide means on said sleeve, a plurality of equally spaced trackways in said plug cooperating with said guide means, each of said trackways comprising a first vertical slot, a horizontal slot communicating therewith and a second vertical slot communicating with said horizontal slot and leading downwardly and outwardly of said plug, the lower portion of said plug body adjacent the second vertical slots being resilient and expanded outwardly and so constructed and arranged to frictionally engage said sleeve and maintain the plug in any of its raised positions.

3. A closure comprising a sleeve, a plug having a plug body slidable in said sleeve, guide means on said sleeve, a plurality of equally spaced trackways in said plug body, each trackway comprising an upper and a lower vertical slot connected by a horizontal slot, said upper slot cooperating with said guide means through which said plug is normally operated, said lower slot leading outwardly of said body, said plug body having a resilient and outwardly expanded portion adjacent the lower slots so constructed and arranged to frictionally engage said sleeve and maintain the plug in any of its raised positions.
